UNITED STATES PATENT OFFICE.

FRANK P. MAIZE, OF PORTLAND, OREGON.

CONTROLLER-REGULATOR.

1,044,212.

Patented Nov. 12, 1912.

Application filed June 3, 1912. Serial No. 701,338.

To all whom it may concern:

Be it known that I, FRANK P. MAIZE, a citizen of the United States, residing at Portland, in the county of Multnomah and State of Oregon, have invented certain new and useful Improvements in Controller-Regulators, of which the following is a specification, reference being had therein to the accompanying drawing.

10 My invention relates to improvements in controller regulators, and more particularly to controllers used on electric railway cars.

The object of my invention is to provide a controller of this character in which the controller arm or crank is regulated so that it cannot be moved instantaneously to a point on the controller where full power is obtained, but has to be turned from point to point as is well understood by those skilled 20 in the art.

Another object of my invention is to provide a simple, cheap and effective regulator which may be readily attached to the ordinary controller having certain details of 25 structure more fully pointed out.

In the accompanying drawings—Figure 1 is a top plan view of a controller box showing my device applied thereto, the working parts being shown in dotted lines. Fig. 2 is 30 a side elevation partly in section of Fig. 1. Fig. 3 is a vertical transverse sectional view taken on the line 3—3 Fig. 1. Fig. 4 is a side elevation similar to Fig. 1, showing the locking or controlling pawl in its locked position. Fig. 5 is a detached perspective view 35 of the locking member. Fig. 6 is a vertical sectional view of the upper end of the controller box, showing my invention applied to the interior of the box and also showing a modified form of the locking member. Fig. 40 7 is a transverse vertical sectional view taken on the line 7—7 of Fig. 6. Fig. 8 is an end view of the locking member of the modified form shown in Figs. 6 and 7.

45 Referring now to the drawing, 1 represents the upper end of the controller box of the ordinary form now used on electric cars. The said controller box is provided with the controller shaft 2, extending upwardly 50 through the upper end of the box. This controller shaft as is well understood by those skilled in the art is adapted to control the power of the motor.

55 Secured to the upper face of the motor is a plate or box-like member 3, having a cen-

tral opening 4, through which the controller shaft 2 freely passes. The said plate 3, as heretofore stated, is of a box-like form having the annular chamber 5 surrounding the shaft 2. Within the said annular chamber 60 adjacent its inner periphery and rigidly secured thereby, are the upwardly projecting lugs 6 having beveled faces 7. These lugs, as is well understood, represent the contact points of the motor and, as shown in Fig. 1, 65 are eight in number. Within the annular chamber 5, adjacent its outer periphery, are lugs 8 having beveled faces 9, which correspond in number to the contact points 6, and are arranged in two groups, one group of 70 three and the other group of four.

The annular central passage 4, through the member 3, has screwed thereon a washer 10, which is adapted to overlap the upper face 11 of the plate or housing 12. This housing, as is shown in Fig. 1, is provided with two upwardly extending lugs 13 and 14 between which extends the controller lever 15, carried by the upper end of the controller shaft 2. By this structure it will be 75 seen that the plate or housing 12 is rotated with the controller lever or crank 15. The plate or housing 12 is provided with an elongated tangentially arranged housing 16 having its lower end communicating with the annular space 5 in the plate 3. The said housing 16 is provided with a transverse shaft 17 locked against rotation by the setscrew 18, and also held against longitudinal movement by the setscrew. Loosely mounted 80 upon the shaft 17 midway its end is a lever 19. Said lever, as shown in Fig. 5, has an enlarged outer end 20 and a reduced end 21 whereby the enlarged end 20 overbalances the reduced end 21 and normally holds the 85 lever in the position shown in Fig. 2 of the drawings. The lower edge of the lever 19 directly below the shaft is provided with a downwardly extended arm 22, which extends within the annular space 5 and in a parallel 90 line with the lugs 6. In Fig. 5 it will be seen that I have shown the arm 22 as separate from the lever 19 and bolted or riveted between ears 23 carried by said lever.

95 Mounted upon the shaft 17 beside the lever 19 is a segment lever 24, which has its outer end provided with downwardly extending dog-shaped member 25, which extends into the annular space 5, and when in 100 the position shown in Fig. 4 of the drawing, 110

engages the lugs 8, whereby the housing 12 is held against rotation and the controller by arm 15. The housing 16, as shown in Fig. 3, of the drawing, is of a width approximately that of the two levers 19 and 24. Within said housing is a ball 26, which rolls upon the upper edges of the levers 19 and 24 and is normally in the right-hand end of the housing 16, as shown in Fig. 2 of the drawing. When in this position the ball overbalances the ends 21 and 25 of the levers 19 and 24 and holds them in the position shown in Fig. 2 of the drawing. When the housing 12 is turned by the controller arm 15, the downwardly depending arm 22 of the lever 19 engages one of the lugs 6 and rocks said lever 19 which causes the ball to roll toward the left of Fig. 2. This ball in its travel to the left rolls upon the upper face 20 of the lever 24, and after it has passed its pivotal connection, causes said lever to swing downwardly and the dog-shaped end 25 engages one of the lugs 8 and the controller arm is locked against further movement. The arm 22 of the lever 19 having passed over the lug 6, the weighted end 20 overbalances the end 21 and the ball, and said ball is caused to travel to the right which again rocks the lever 24, withdrawing 25 the dog-shaped member 25 from engagement with the lug 8, which releases the housing 12. The operation just described allows the controller arm 15 to be turned to the next lug 6, corresponding to the points 30 on the controller and the operation is again repeated. By this structure it will be readily seen that it is impossible for the controller arm 15 to be turned more rapidly around, as it is necessary for the controller 35 arm to come to a standstill for a short period at each lug 6, representing the points on the motor. This period of time at which the lever is held is very short as it is only necessary for the ball 26 to roll from the 40 right-hand end of the housing 16 to the left and back again. The housing 3 is provided with a setscrew 3' which is adapted to engage a lug 15' carried by the lower face of the controller arm 15, whereby the movement of the lever is controlled and regulated.

In Figs. 6, 7 and 8 instead of having my improved device applied to the upper face of the controller box 1, I have shown it applied within the controller box. In this 45 view, 2 is the controller shaft the same as shown in the preferred form and is provided with a controller arm. Carried by said controller shaft 2, within the controller box is a disk 27, keyed upon the shaft. The 50 said disk is provided with the lugs 6 and also the lugs 8 corresponding to those shown in Figs. 1 and 2 of the drawing. Secured to the lower face of the upper end of the controller box 1, is a downwardly depending lug 28' in which is mounted a shaft

29, upon which is loosely mounted the housing 28. One end of the housing 28 is thickened as indicated at 30 and forms a dog adapted to engage the lugs 8, as will be hereinafter more fully described. Loosely 55 pivoted upon the shaft 29, intermediate its ends, is a lever 31, which has its end 32 thickened so as to form a weight to overbalance the end 33. The said lever 31 directly below the shaft 29 is provided with a ratchet arm 34 adapted to engage the lugs 6, representing or indicating the points of the controller. The lever 30, as shown in Fig. 7 of the drawing, is of a width equal to the interior width of the housing 28. Within 60 the housing above the lever 31, is a ball 35 which rests upon the upper face of the lever and is normally held in the right-hand end of the housing 28. The rotation of the controller shaft 2 causes the disk 27 to rotate therewith and the arm 34 is engaged by one of the lugs 6. This causes the lever 31 to rock upon the shaft 29 throwing the weighted end of the lever upwardly, causing the ball to roll to the left and overbalance the housing 28 causing its thickened end 30 to move downwardly and engage one of the lugs 8, whereby the disk 27 and the shaft carrying the same are locked against rotation. The arm 34 of the lever 31 having 65 passed the lug 6, the weighted end 32 causes the ball 35 to roll to the right which overbalances the weighted end 30 of the housing 29 and unlocks the disk 27, as is readily seen from the drawings.

From the foregoing description, it will be seen that the controller arm cannot be rapidly turned, to turn on the current and thus prevent the car from being suddenly started. The beveled faces of the lugs 6 and 70 8 allow the controller arm to be swung rapidly around so that the current can be instantaneously cut off.

Having thus described my invention, what I claim and desire to secure by Letters Patent is:

1. The combination of a controller and controller arm, of means for stopping the controller arm for a short period of time at each point on the controller and a weight movable on said stopping means for operating the same.
2. The combination with a controller and controller arm, of a pivoted lever for stopping the controller arm for a short period of time at each point on the controller, and a weight movable on said pivoted lever for operating the same.
3. The combination with a controller and controller arm, of an intermediately pivoted lever adapted to lock the controller arm for a short period of time at each point on the controller, and a weight movable on said intermediately pivoted lever for operating the same.

4. The combination with a controller and controller arm, a pivoted lever adapted to lock the controller arm for a short period of time at each point on the controller and a ball rolling on said lever for controlling the same. 5
5. The combination with a controller and controller arm, of a pivoted lever carried by the controller, a ball rolling on said lever and means for moving the ball on the lever. 10
6. The combination with a controller and controller arm, of a weighted lever adapted to lock the controller for a short period of time at each point on the controller, automatic means for operating said lever, and means operated by the movement of the controller arm for operating said locking means. 15
7. The combination with a controller and controller arm, of a pivoted weighted lever, a ball normally held upon the weighted end of the lever, means operated by the movement of the controller arm for causing the ball to travel to the opposite end of the lever and locking the controller arm against movement for a short period of time. 20
8. The combination with a controller and controller arm, of an intermediately pivoted lever weighted at one end, a ball traveling on the upper face of said lever, means operated by the movement of the controller arm for causing the ball to travel to the opposite end of the lever, and means operated by the weight of the ball for locking the controller arm against movement for a short period of time. 25
9. The combination with a controller and controller arm, of an intermediately pivoted dog carried by the controller arm and operated by the movement of the controller for locking said arm for a short period of time and a ball controlling said dog. 40
10. The combination with a controller and controller arm, of a housing carried by the controller arm, an intermediately pivoted dog for locking the controller arm for a short period of time and automatic means for releasing said locking means and a ball controlling said dog. 45
- 50 11. The combination with a controller and controller arm, of lugs carried by the upper faces of the controller, an intermediately pivoted dog carried by the controller arm and adapted to lock the controller arm for a short period of time, and a movable weight supported by the lever and engaging the lugs for operating said dog.
12. The combination with a controller and controller arm, a controller shaft carried by the controller arm, lugs carried by the upper face of the controller around said shaft, a dog adapted to lock the controller against rotation and a movable weight supported by the dog and engaged by the lugs for operating the dog operating means. 60
13. The combination with a controller and controller arm, of a shaft carried by the controller arm, lugs carried by the upper face of the controller and surrounding the shaft, a second series of lugs carried by the controller and surrounding the shaft, a housing carried by the controller arm, an intermediately pivoted dog adapted to engage the second series of lugs for locking the controller arm against rotation, a lever carried by the housing and means carried by the lever and engaged by the first set of lugs for operating the said dog. 70
14. The combination with a controller and controller arm, a controller shaft carried by the controller arm, a series of lugs carried by the upper face of the controller and surrounding the shaft and a second series of lugs carried by the upper face of the controller and surrounding the shaft, a housing carried by the controller arm, a transverse shaft extending through the housing, an intermediately pivoted dog carried by said shaft and adapted to engage a second series of lugs, an intermediately pivoted weighted lever carried by the said shaft within the housing and means carried by the said lever for engaging the first series of lugs and having means for operating the dog whereby the dog is caused to engage the second series of lugs for locking the controller arm against movement for a short period of time. 80
15. The combination with a controller and controller arm, of a controller shaft carried by the controller arm, a series of lugs carried by the upper face of the controller and surrounding the shaft, a second series of lugs carried by the upper face of the controller and surrounding the shaft, a housing carried by the controller arm, a transverse shaft in said arm, an intermediately pivoted dog mounted on said shaft and one end adapted to engage the second series of lugs and intermediately pivoted weighted lever mounted upon said shaft, a ball within the housing and normally held upon the weighted end of the lever and rolling thereon, an arm carried by the lever and engaging the first series of lugs, whereby the lever is locked and the ball is caused to travel to the left and force the dog down into engagement with the second series of lugs whereby the controller arm is locked against movement for a short period of time. 90
16. The combination with a controller and controller arm, of a pivoted housing carried by the controller, a disk movable with the controller arm, an intermediately pivoted member within the housing, a ball within the housing for rolling on the intermediately pivoted member, an arm carried by the intermediately pivoted member and engaged by the disk for locking said arm, a ball within the housing and rolling on said lever, whereby the lever and the housing are 100
- 110
- 115
- 120
- 125
- 130

rocked upon their pivots to cause one end of the housing to engage the disk and lock the controller arm for a short period of time.

17. The combination with a controller and controller arm, a pivoted lever adapted to lock the controller arm for a short period of time, at each point of the controller, and a weight supported by and controlling said lever and longitudinally movable thereon.
18. The combination with a controller and a controller arm, an intermediately pivoted lever adapted to lock the controller arm for a short period of time at each point on the controller and a weight supported by and controlling said lever and longitudinally movable thereon.
19. The combination with a controller and controller arm, of an intermediately pivoted lever adapted to lock the controller arm for a short period of time at each point of the controller, a second lever operated by the movement of the controller arm, a weight supported by said second lever and longitudinally slidable thereon and adapted to operate the intermediately pivoted lever, 20 substantially as shown and described.

In testimony whereof I hereunto affix my signature in the presence of two witnesses.
